[57] **CLAIM**

The ornamental design for a toothpaste dispensing toothbrush system, as shown.

DESCRIPTION

FIG. 1 is an exploded left side elevational view of a toothpaste dispensing toothbrush system showing my new design, shown with the toothpaste cartridge removed from the handle for clarity of illustration only;

FIG. 2 is a right side elevational view thereof;

FIG. 3 is a front elevational view thereof;

FIG. 4 is a rear elevational view thereof;

FIG. 5 is a top plan view thereof; and,

FIG. 6 is a bottom plan view thereof.
